UNITED STATES PATENT OFFICE.

JOHN THOMAS TROTTER, OF BROOKLYN, NEW YORK.

ELECTRIC FITTING.

Application filed April 28, 1922. Serial No. 557,154.

To all whom it may concern:

Be it known that I, JOHN THOMAS TROTTER, a citizen of the United States, and a resident of the city of New York, borough of Brooklyn, in the county of Kings and State of New York, have invented a new and Improved Electric Fitting, of which the following is a full, clear, and exact description.

10 The present invention relates to new and useful improvements in electric fittings, and it pertains more particularly to fittings for electric lamps.

15 It is one of the primary objects of the present invention to provide a new and improved form of electric fitting adapted for use in connection with electric lamps made in imitation of candles.

20 It is a further object of the invention to provide a fitting of this character in which the ordinary switch key is dispensed with.

25 It is a further object of the invention to construct the fitting so that it may be self-contained within a shade or the like in imitation of a candle, thus rendering the imitation more complete.

With the above and other objects in view, reference is had to the accompanying drawings, in which—

30 Figure 1 is a longitudinal sectional view of an electric fitting constructed in accordance with the present invention;

Fig. 2 is a view partly in elevation and partly in section, taken at right angles to Fig. 1;

Fig. 3 is a detail sectional view of the interior structure of the fitting;

Fig. 4 is a top plan view of that portion of the device shown in Fig. 2;

40 Fig. 5 is a horizontal sectional view taken on the line 5—5 of Fig. 1, with the outer shell removed;

Fig. 6 is a horizontal sectional view taken on the line 6—6 of Fig. 1, with the outer shell removed.

Referring more particularly to the drawings, the reference character 10 designates an arm or bracket and secured to the outer end thereof is an ornamental fitting 11. 50 This ornamental fitting 11 forms the base of the electric fitting of the present invention, and it serves to support the same in operative position. Rigidly carried by the fitting 11, is a tubular member 12, and said tubular member carries on its upper end a block 13 of insulating material. This block

13 of insulating material is secured in position on the upper end of the tubular member 12 by means of a nut 14, said nut having screw-threaded engagement with the upper end of the member 12.

60 Mounted upon the upper end of the block 13 is a lamp socket 14, said socket 14 being adapted to receive an incandescent lamp 15 therein in the ordinary manner. The screw-threaded nut 14' hereinbefore mentioned is provided with wings 16 or the like, which project therefrom, and said wings 16 are adapted to be secured to portions 17 of the block 13 by means of small screws, bolts, or 70 the like, 18.

75 The reference character 19 designates the electric current conductors and one of said electric current conductors is connected to a screw 20 carried by the block 13 near the lower end thereof, the other conductor being connected by means of a screw 21 to the block 13 near its upper end. The screw 20 also serves to secure a contact plate 22 to the block 13 while the screw 21 serves to secure a contact plate 23 to the block 13. This contact plate 23 forms a part of the lamp socket 14, as more clearly shown in Fig. 4, and said lamp socket is placed by this construction into circuit with the electricity 85 conductor.

80 Surrounding the tubular member 12 is a tubular member 25, and said tubular member 25 is rotatably mounted on said tubular member 12. Threaded onto the lower end 90 of the tubular member 25 as at 26, is a disk 27 or the like, and said disk 27 serves as the means by which the tubular member 25 is rotated about the tubular member 12.

95 The lower end of the block 13 is provided with a cut-out portion 28, and rotatably mounted in said cut-out portion 28 is a block 29 of non-conducting material. This block of non-conducting material is carried by a member 30, which in turn is connected 100 as at 31, by screw threads to the upper end of the tubular member 25 in such a manner that as the tubular member 25 is rotated, the block 29 will be rotated in the cut-out portion 28. Carried by the block 29 are two 105 contact plates 32 and 33, said contact plates being diametrically disposed with respect to one another. These contact plates are connected by means of a ring 34 carried by the top face of the block 29.

110 Leading from the lower end of the block 13 to the upper end thereof is a conductor

40, and said conductor 40 has its upper end bent at right angles to provide a contact 41 lying in the bottom of the socket member 14, the socket member 14 being cut out as indicated at 42 to receive the member 41. This contact member 40 is secured to the block 13 in such a manner that as the block 29 is rotated so that its contact 32 engages the contact 22, the contact 33 of the block 10 29 will engage the lower end of the conductor 40, as at 43.

Secured in the ornamental fitting 11, is a partition 45, and said partition 45 carries a plurality of resilient members 46. These 15 resilient members 46 are adapted to engage notches 47 in the bottom face of the disk 27, to retain the several parts in either the "on" or "off" position.

Surrounding then entire structure is a 20 tubular member 50 of porcelain or other suitable material in imitation of a candle, and said tubular structure is adapted to rest upon the disk 27 as clearly shown in Fig. 1.

The device operates in the following 25 manner:

When the several parts are in the position shown in Fig. 1, the circuit to the lamp 15 is complete, the current passing from one of the conductors 19 to the contact plate 22, 30 to the contact plate 32, around the ring 34 to the contact plate 33, through the conductor bar 40, member 41, through the lamp, through the socket 14, contact plate 23, to the other conductor.

35 When it is desired to extinguish the light, it is only necessary to rotate the disk 27 when the block 29 will be rotated through the medium of the tube 25, and move the contact plates 33 and 32 out of contact with 40 the contact plate 22 and the conductor bar 40, respectively, thus breaking the circuit to the lamp 15.

With the several parts in either of these 45 positions, the resilient members 46 will engage the notches 47 to retain the parts against accidental displacement, thus giving to the device all of the advantages of a snap switch.

While in the present instance but a single 50 form is shown, it is obvious that various modifications and arrangements of parts may be resorted to without departing from the spirit of the invention and the scope of the appended claims.

55 What is claimed is:

1. A device of the character described comprising a tubular member, a second tubular member rotatably mounted thereon, an insulated block carried by said first- 60 mentioned tubular member, electrical conductors extending through the first-mentioned tubular member, a lamp socket carried by said block, a plurality of contact

plates carried by said block, one of said conductors being in circuit with the lamp socket, 65 the other conductor being connected to one of said contact plates, and means carried by the second-mentioned member and adapted upon rotation thereof to engage two of the contact plates and establish a 70 circuit from the conductors through the lamp socket.

2. A device of the character described comprising a tubular member, a second tubular member rotatably mounted thereon, 75 an insulated block carried by said first-mentioned tubular member, electrical conductors extending through the first-mentioned tubular member, a lamp socket carried by said block, a plurality of contact plates carried by said block, one of said conductors being connected to one of said contact plates, the other conductor being connected to said lamp socket, means carried by the second-mentioned member and adapted upon rotation thereof to engage two of the contact plates and establish a 80 circuit from the conductors through the lamp socket, and means for limiting the rotary movement of said second-mentioned tubular member. 85

3. A device of the character described comprising a tubular member, a block of insulating material carried thereby, a plurality of contact plates carried by said block of insulating material, a lamp socket carried 95 thereby, a plurality of electrical conductors extending through said tubular member, one of said conductors being connected to the lamp socket, the other of said conductors being connected to one of said contact plates, 100 and means rotatably mounted on the tubular member and adapted to establish connection between the contact member to which one of the electrical conductors is connected and said socket. 105

4. A device of the character described comprising a tubular member, a block of insulating material carried thereby, a lamp socket carried by said block of insulating material, a plurality of electrical conductors 110 extending through said tubular member, one of said conductors being connected to the lamp socket, a plurality of contact plates carried by said block of insulating material, means for connecting the other of said conductors to one of said contact plates, a conductor extending from one end of the block of insulating material to a point adjacent the lamp socket and adapted to form one of the contact points of said lamp socket, and rotatable means adapted for movement about the tubular member to establish connection between the electric conductors through said lamp socket. 115 120
